RAYMOND A. WALTER, OF NEW YORK, N. Y., ASSIGNOR TO CONVEYOR SALES COMPANY, OF NEW YORK, N. Y., A CORPORATION OF NEW YORK

DRIVING MECHANISM FOR RECIPROCATING CONVEYERS

Application filed July 1, 1927. Serial No. 202,912.

This invention relates in general to conveyor motors and more particularly has reference to a driving mechanism for reciprocating conveyors.

Previous to this time motors of this character embodying a mechanism for translating rotary motion into reciprocating motion for operating reciprocating conveyors, have had the motion translating mechanism assembly set up in a vertical plane necessitating a needlessly high construction of the motor and restricting installation in works having little head room such as is often encountered in mines and other industrial projects where reciprocating conveyors find application.

The conventional crossheads operated by the motion translating mechanism through connecting rods have heretofore been operated in insecure guides and the downward thrust and twisting effect of the connecting rod transmitted through the crosshead to the guides has worked to materially hamper and shorten the life of the motors.

The crossheads in previous drives have also been extremely short and pivoted to fixedly fulcrumed driving levers by short connecting rods to prevent sidewise play and compensate for the pendulum shortening effect of the driving lever during operation. These rods do not effectually eliminate the pendulum strains in the driving lever and will not allow adjustment of the lever to vary the length of the conveyor stroke.

The driving mechanisms heretofore employed have not been provided with efficient lubricating systems which are so necessary to conveyor motors because of the friction unavoidably developed in all parts of the mechanism during operation.

The floors of mines and similar workings generally present irregular surfaces for the mounting of driving engines and it has been necessary in the past to construct concrete or masonry foundation piers to afford a secure mounting for the mechanism.

An object of this invention is to provide a driving mechanism for a reciprocating conveyor constructed to afford a maximum compactness of assembly.

Another object of this invention is to pro-

vide a driving mechanism for a reciprocating conveyor constructed to efficiently withstand the internal stresses and strains developed by the motion translating mechanism.

Still another object of this invention is to provide a driving mechanism for a reciprocating conveyor adapted to eliminate pendulum strains in the driving mechanism and afford adjustment to vary the stroke of the conveyor.

A further object of this invention is to provide a driving mechanism for a reciprocating conveyor having a lubricating system cooperating with the driving mechanism to efficiently lubricate all parts of the mechanism.

A still further object of this invention is to provide a mounting for a reciprocating conveyor that may be positioned on uneven surfaces and adapt itself to the irregularities of the working without giving rise to stresses or strains in the mechanism.

With these and other objects in view which may be incident to my improvements, the invention consists in the parts and combinations to be hereinafter set forth and claimed, with the understanding that the several necessary elements comprising my invention, may be varied in construction, proportions and arrangement, without departing from the spirit and scope of the appended claims.

In order to make my invention more clearly understood, I have shown in the accompanying drawings means for carrying the same into practical effect, without limiting the improvements in their useful applications to the particular constructions, which for the purpose of explanation, have been made the subject of illustration.

In the drawings forming a part of this specification:

Figure 1 is a top view of the driving mechanism comprising the subject matter of this invention;

Fig. 2 is a side elevational view showing the housing in section;

Fig. 3 is a side elevational view of the method of mounting the driving mechanism.

Fig. 4 is a side view showing the preferred

form of motion translating mechanism to attain compactness of assembly;

Fig. 5 is a side view showing a modified form of motion translating mechanism of a more simple arrangement of levers than that shown in Fig. 3.

Referring by numerals to the drawings wherein the same and similar elements are designated by like symbols of reference throughout, and more particularly to Figure 1, there is shown the improved conveyor driving mechanism forming the subject matter of this invention. The driving mechanism comprises a casing 1, composed of any suitable metal, as shown in Figure 2, having integral supporting legs 2 and 3 on each end. A bearing 4 is formed midway on one internal wall and a similar bearing 5 formed near the end of the wall in co-axial alignment with the bearing 4. The bearing 5 is provided with an integral shoulder 6' for a purpose to be hereinafter set forth.

The casing 1 comprises a body portion 6 and extended shoulder portions 7 and 8. The shoulder portion 7 is formed with an internal thickened portion 10 to add rigidity to the casing and the body portion 6 is provided with an outer integral seat 9 adapted to receive a prime mover 11, operating a driving shaft 12.

The prime mover may be an electric motor as shown, although it is manifest any other suitable source of power may be substituted therefor, if so desired, or the mechanism driven by a prime mover stationed apart from the drive.

The drive shaft 12 is journaled in one wall of the extended shoulder portion 8 in the casing and positioned by a collar 13. A pinion 14 is keyed on the driving shaft 12 adapted to mesh with a pinion 15 keyed on a shaft 16 having one end journaled in the side of the extended shoulder portion 8 in the casing and the other end journaled in a bearing formed in the shoulder 6 projecting from the bearing 5.

There is also keyed on the shaft 16 a pinion 17 adapted to mesh with a pinion 18 keyed on one end of a shaft 19. The respective ends of the shaft 19 are journaled in a plurality of bearing supports 21 and 22 mounted on the bottom of the casing 1. A pinion 23 is keyed on the other end of the shaft 19 adapted to mesh with a pinion 24 keyed on a shaft 25. The respective ends of the shaft 25 are journaled in the bearing supports 21 and 22 in alignment with the bearings supporting the shaft 19. A pinion 26 is also keyed on the shaft 25 adapted to mesh with a corresponding pinion 27 keyed on a shaft 28 also journaled in the bearing supports 21 and 22, in alignment with the shafts 19 and 25.

The pinion 14, cooperating through the intermediate pinions constitute a series of speed

reducing gears to transmit the rotary motion imparted by the drive shaft 12 to the shaft 28 at a moderated speed. A crank arm 29 is mounted on one end of the shaft 28 and adapted to rotate therewith.

One end of a connecting rod 31 is mounted on the crank arm by a crank pin 32. The other end of the connecting rod 31 is pivoted to a rocking lever 33 by a pin 34. The rock lever 33 is fulcrumed at its base by a pin 35, projecting through the side walls of the extended shoulder portion 7 of the casing 1, and held in position by a collar 36.

The rocking lever 33 is formed with an intermediate wall 37 adapted to position the connecting rod 31 on the pin 34. A connecting rod 38 is pivoted to the bottom of the rocking lever by a pin 39. The connecting rods 31 and 38 are pivoted on the rocking lever 33 in offset relation separated by the intermediate wall 37.

The other end of the connecting rod 38 is pivoted in a slot formed in one end of a crosshead 41 by a pin 42. The crosshead 41 is adapted to slide in the bearings 4 and 5 formed integral with the wall of the casing 1. The crosshead 41 is provided with a central slot adapted to receive a driving lever 43 provided with a series of apertures 44. The driving lever 43 is secured to the crosshead by a pin 45 projecting through one of the holes 44. One end of the driving lever 43 reciprocates freely with the crosshead 41 and the other end is fulcrumed in a slot in the end of a sliding crosshead 46 and held by a pin 47 journaled in a bearing formed in the support 21.

The end of the crosshead 41 is provided with a central aperture adapted to receive a barrel 48 of a pump 49. The pump 49 is held in a casing 50 mounted on the side wall of the casing on the extended shoulder 8. A plunger 51 is centrally positioned in the base of the aperture in the crosshead adapted to reciprocate concomitantly therewith, and slide in and out of the barrel 48. The movement of the plunger 51 is adapted to force lubricant by the normal action of conventional ball valves 52, through an oil line 53. The oil line 53 is provided with a series of nozzles 54 and terminated with a nozzle 55 variously positioned over the pinions and rocking lever.

The legs 2 and 3 formed integral with the bottom of the rigid casing 1 are mounted on a flexible metallic bed plate 56 and positioned throughout by angles 57 or by any other suitable means, such as bolts. The bed plate is formed with upturned ends 58 and 59 to afford facility of transport and placement. The top of the casing is provided with a cover 61 fastened by any suitable means to prevent foreign material entering the driving mechanism.

In Figure 4, the connecting rod 38 is shown pivoted on the same side of the rocking lever

as the connecting rod 31. By thus mounting is substantially the reverse of the forward the two connecting rods in the same plane, stroke, that is, from momentary rest at the rather than offset, a more compact assem- beginning thereof, the velocity rapidly in- bly may be attained.

There is shown in Figure 5, a modification 5 of the rocking lever arrangement illustrated in Figures 1, 2, and 3. An arm 62 is pivoted on the fulcrum pin 35 and on the pin 39 with a sheave strap 63, mounted on an eccentric 64 keyed on the shaft 28. There is also mounted on the pin 39 the connecting rod 38 pivoted on the crosshead 41. This assembly attains the same motion with a more simple arrangement of levers but requires added height in the assembly of the motor which is objectionable if its use is desired in operations having little head room.

There is shown in Figure 3 the preferred 20 method for installation according to this invention in underground mine workings having a roof indicated by the numeral 65 and a floor indicated by the numeral 66. The floor and roof in workings of this character are usually rock, although coal or other va-

25 rieties of mineral matter form supports that will usually be found sufficiently firm to employ the method of anchorage forming a part of this invention. The driving mechanism is placed on the floor 66 and firmly 30 plugged or wedged into position and notches 67 cut in the roof 65. Jack screws 68 are inserted in indentations 69 formed in the bed plate 56 and tightened in the notches 67. A mounting of this character by the action 35 of the flexible bed plate allows a distribution of stresses and relieves the strains in the motor that attend the unyielding foundations previously employed.

The operation of this invention may be 40 readily understood by first having reference to Figure 2. The driving mechanism is

fastened to a reciprocating conveyer by a clevis 71 or other suitable attaching means, pivoted on the driving lever 43 by a pin 72. The motion translating mechanism is oper- 45 ated by the rotary crank arm 29 and imparts reciprocating motion to the crosshead 41 through the toggle joint formed by the end of the connecting rod 38 and the pin 42. The

50 accelerated and retarded reciprocation necessary to efficient conveyer operation is attained in this assembly. By accelerated and retarded reciprocation will be under-

55 stood the forward and backward movement of a conveyer accomplished by one revolution of a rotary source of power. The conveyer from momentary rest on the beginning of the forward stroke increases slowly in velocity for substantially two-thirds of its 60 distance of travel where it rapidly decreases in velocity the remainder of the forward stroke coming to momentary rest at the end thereof before the beginning of the backward stroke, at a half revolution of the rotary source of power. The backward stroke

70 beginning thereof, the velocity rapidly increases for substantially one-third of its distance of travel when it slowly decreases in velocity the remainder of the backward stroke coming to momentary rest at the end before the beginning of the successive forward stroke, after a full revolution of the rotary source of power.

75 The advantages residing in the operation of a reciprocating conveyer in this manner will be apparent. The material transported moves forward with the conveyer on the forward stroke for substantially two-thirds of its length whereupon the conveyer is drawn forward from under the material thereon for the remainder of the forward stroke. On the beginning of the backward stroke, the conveyer is drawn back from under the material for substantially one-third of its length, advancing the same, and carrying the material backward with decreasing velocity for the remainder of the stroke.

80 The crank pin 32 engaging with the connecting rod 31 mounted on the rocking lever 33 by the pin 34 translates the rotary motion of the motor 11 into an oscillating motion of the rocking lever 33, oscillating on the ful-

85 crum pin 35. As the rocking lever 33 oscillates the pin 39 rises and falls carrying with it the connecting rod 38 pivoted in the slot 35, the rock lever 33, the pin 39, the connecting rod 38, and the pin 42, form in effect a toggle joint. The fulcrum pin 35 is firmly 90 fastened in the extended shoulder 7 formed on the casing. The crosshead 41 slides

95 freely in the guide bearings 4 and 5 and is drawn back and forth by the connecting rod 38.

100 The operation of this invention may be readily understood by first having reference to Figure 2. The driving mechanism is fastened to a reciprocating conveyer by a clevis 71 or other suitable attaching means, pivoted on the driving lever 43 by a pin 72. The motion translating mechanism is oper- 105 ated by the rotary crank arm 29 and imparts reciprocating motion to the crosshead 41 through the toggle joint formed by the end of the connecting rod 38 and the pin 42. The

110 pin 39, is extremely small in proportion to the movement of the crank. When the crank 29 is in a horizontal position, as shown in Figure 2, the movement of the crosshead 41 caused by the rise of the pin 39, is extremely small in proportion to the movement of the crank. When the crank is rotated through 180° the pin 34 is drawn through the toggle joint formed by the end of the connecting rod 38 and the pin 42. The pin 39 reaches the highest point. At this

115 highest point a small progress in the movement of the crank 29 imparts a greater movement than is transmitted when the crank is in the horizontal position.

120 The motion imparted to the reciprocating crosshead 41 is transmitted to the shaker conveyer through the driving lever 43 connected to the conveyer by the clevis 71, pivoted by the pin 72. One end of the driving lever 43 reciprocates freely with the cross-

125 head 41, the other end fulcrums on the pin 47 pivoted to the sliding crosshead 46 operating in the bearing formed in the support 21. The connections between the crosshead 41, driving lever 43 and the crosshead 46 form a

130 three point suspension that makes the ele-

ments self aligning and reduces the strain on the mechanism.

As the driving lever 43 is reciprocated, the distance between the crosshead 41 and the fulcrum pin 47 measured at right angles to the crosshead 41 constantly shortens and lengthens requiring the crosshead 46 to be mounted so that it may freely reciprocate to compensate for this shortening and lengthening effect. This construction entirely eliminates the pendulum strains found in previous levers and affords a simple method of adjusting the stroke of the lever by withdrawing the pin 45, securing the driving lever 43 to the crosshead 41 and replacing the pin in any one of the desired connecting apertures to attain the desired length of stroke. As the pin 45 is then reinserted and as the difference between the aperture 44 and the fulcrum 47 is greater or less, according to the particular one chosen, the lever will reciprocate through a greater or lesser distance as the distance from the hole 46 to the driving connection 71 is changed.

The mechanism is lubricated by oil from the nozzles 54 and 55 projecting from the oil line 53. The bottom of the casing is filled with a suitable lubricant to the proper depth, so that the crosshead 41 is partially submerged and the pump 49 may operate freely to force the oil through the line where it will be discharged through the nozzles and returned to the bottom to be recirculated.

The casing 1 is supported as previously described, as shown in Figures 2 and 3, on integral end legs 2 and 3 resting on a flexible bed plate 56 and held by angles 57. As the casing 1 does not rest on the bed plate 56 through its entire length but only contacts on the legs, a considerable space is left between the body of the casing and the bed plate, permitting the flexible bed plate to take up stresses when the mechanism is secured in position on an uneven surface and relieve strains in the motor as the bed plate flexes around and over irregularities and prevents stresses being imparted to the rigid frame of the casing.

The mechanism first being firmly mounted or wedged in position on the floor, as shown in Figure 3 and notches cut into the roof, the jack screws are inserted in the notches and indentations provided on the bed plate and adjusted to effectually anchor the driving mechanism in position.

There is accomplished by this invention a driving mechanism for a reciprocating conveyer attaining a lower assembly than heretofore achieved having a three point suspension drive affording a self aligning mechanism relieving strains and stresses on the mechanism, and freely lubricated in cooperation with the driving mechanism. There is further accomplished a method of mounting, dispensing with the foundations previously

employed and rendering greater ease and security of anchorage and eliminating strains in the driving mechanisms.

While I have shown and described the preferred embodiment of my invention, I wish it to be understood that I do not confine myself to the precise details of construction herein set forth, by way of illustration, as it is apparent that many changes and variations may be made therein, by those skilled in the art, without departing from the spirit of the invention, or exceeding the scope of the appended claims.

I claim:

1. A driving motor for a reciprocating conveyer embodying a motion translating mechanism comprising a connecting rod having one end eccentrically mounted on a rotary power transmitting device and the other end pivoted to a fulcrumed rocking lever, and a connecting rod having its respective ends pivotally mounted on the fulcrumed rocking lever, in offset relation with respect to the first connecting rod, and to a reciprocating member operating in a longitudinal plane, and floatable means to drive the conveyer.

2. A driving motor for a reciprocating conveyer embodying a motion translating mechanism comprising a crank arm mounted on a rotary power transmitting device, a connecting rod having one end mounted on the crank arm and the other end pivoted to one corner of a three cornered rocking lever fulcrumed at one corner, and a connecting rod having its respective ends pivotally mounted on the third corner of the rocking lever in offset relation with respect to the first connecting rod and to a reciprocating crosshead carrying a floated member adapted to afford reverse uniformly long and short accelerated and retarded strokes of reciprocating motion, and means to drive the conveyer.

3. A driving motor for a reciprocating conveyer embodying a housing support comprising a flexible bed plate, a casing having integral supporting legs resting on the bed plate, means to fix the casing on the bed plate and means formed in the housing to receive the driving motor.

4. A driving motor for a reciprocating conveyer embodying a housing comprising a flexible bed plate having upturned ends, a casing having integral end supporting legs resting on the bed plate, means to fix the casing on the bed plate, and means formed in the housing to receive the driving motor.

5. A driving mechanism for a reciprocating conveyer comprising a casing, rigid integral projections formed on the bottom of the casing and means to support the casing on a flexible bed plate.

6. A driving mechanism for a reciprocating conveyer comprising a rotary source of power, motion translating devices operated thereby, a crosshead driven through the mo-

tion translating devices, a driving lever pivoted on the crosshead, means to floatably anchor one end of the driving lever and means to connect the other end to the conveyer.

6 7. A driving mechanism for a reciprocating conveyer comprising rotary source of power, motion translating devices operated thereby, a crosshead driven through the motion translating devices, a driving lever extending through and pivoted in a slot provided in the crosshead, means to floatably anchor one end of the lever, means to connect the other end to a conveyer and means to adjust the position of the lever in relation 10 to the crosshead to vary the stroke.

15 8. A driving mechanism for a reciprocating conveyer comprising a casing, a rotary source of power associated therewith, a crank connected through reducing gears to the rotary source of power, a crosshead driven by the crank through a fulcrumed rocking lever, a driving lever having one end floatably anchored, pivoted on the crosshead, the other end being adapted to be connected to a conveyer to impart reverse uniformly long and short accelerated and retarded strokes, means provided in the casing to maintain the crosshead submerged in lubricant, means operated by the crosshead to spray lubricant over 20 the mechanism, and a flexible bed plate supporting the casing to relieve strains in the driving mechanism.

25 9. A driving motor for a reciprocating conveyer embodying a housing support, comprising a flexible bed plate, a casing having integral supporting legs resting on the bed plate and fixed thereto, means formed in the housing to receive the driving motor and means to anchor the bed plate on the floor of a working between the top of the bed plate and the 30 roof of the working.

35 10. A driving motor for a reciprocating conveyer embodying a housing support comprising a bed plate formed with turned up 40 ends, a casing with integral supporting lugs having a bottom portion of smaller dimensions than the bed plate resting thereon and fixed thereto, and extensible members for fitting between the top of the bed plate and the 45 roof of a working to anchor the motor on the floor of the working.

50 In testimony whereof I affix my signature.

RAYMOND A. WALTER.
